UNITED STATES PATENT OFFICE

2,530,850

HOSE SUPPORTER

Lela F. Atchley, Oklahoma City, Okla.

Application August 18, 1949, Serial No. 110,925

1 Claim. (Cl. 2-306)

1

This invention relates to hose supporters for use by women, and has particular reference to hose supporters of that type which include a belt or body-encircling band, and elastic straps depending from said belt or band, and having hose-engaging clasps at their lower ends.

The primary object of the invention is to provide an improved belt or band for hose supporters of the above type which will be comfortable to wear and will not press objectionably against the wearer's abdomen.

Another object is to provide a hose supporter of the above type having a novel and efficient arrangement of depending elastic clasp-carrying straps which will properly support the hose at all times without tearing the same.

In the accompanying drawing:

Figure 1 is a plan view of a hose supporter embodying the present invention.

Figure 2 is a front view of the hose supporter as it appears in use.

Figure 3 is a rear view of the hose supporter as shown in Figure 2.

Figure 4 is a side view thereof.

Figure 5 is a vertical section taken on the line 5-5 of Figure 1.

Figure 6 is a fragmentary horizontal section taken on the line 6-6 of Figure 1.

Referring in detail to the drawing, the present hose supporter includes a wide inelastic fabric belt or band 5 adapted to rest on the hips and to encircle the body just below the waistline, said belt or band having a short elastic strap 6 attached to one end thereof adapted to be connected to the other end of the belt or band at the back of the wearer by hooks 7 and coacting eye members 8, or the like. The belt or band 5 is composed of two substantially similar sections 9 and 10 having their edges bound with tape 11 and provided with scalloped lower edges affording a front scallop 12, a side scallop 13, and a rear scallop 14 for each section. The end edges 15 and 16 of each section are inclined and extend in downwardly converging relation, and the ad-

jacent or inner ends of the sections are partially overlapped, are stitched together at the top as at 17, and are otherwise free of connection with each other. Thus, the adjacent ends of the sections may freely move relatively to suit changes of posture and avoid objectionable pressure on the abdomen.

Attached to each scallop of each band section is a depending adjustable elastic strap 18 having a hose engaging clasp 19 at its lower end. Thus, clasps are provided to engage each hose at the front, the back, and the outer side so as to properly support the hose at all times without tearing the same.

Having described the invention, what is claimed as new is:

A hose supporter comprising a wide inelastic fabric belt adapted to encircle the body entirely below the waist line and having means to separably connect the ends thereof at the back of the wearer, said belt comprising two substantially similar sections having adjacent ends partially overlapped at the front of the band and stitched together at the top but otherwise free of connection with each other, and front, side and rear depending elastic straps attached to each section and having hose-engaging clasps at their lower ends, said adjacent ends of the sections having oppositely inclined downwardly diverging end edges and being provided with a scalloped lower edge providing front, rear and side scallops, each scallop having one of said depending elastic straps attached thereto.
